UNITED STATES PATENT OFFICE

169,632

WALL COMB HOLDER

Walter F. Pfarrer, Beaver Dam, Wis.

Application November 28, 1952, Serial No. 22,475

Term of patent 7 years

(Cl. D86—10)

To all whom it may concern:

Be it known that I, Walter F. Pfarrer, a citizen of the United States, residing at Beaver Dam, in the county of Dodge and State of Wisconsin, have invented a new, original, and ornamental Design for a Wall Comb Holder, of which the following is a specification, reference being had to the accompanying drawings, forming a part hereof.

I claim:

The ornamental design for a wall comb holder, as shown.

WALTER F. PFARRER.
